Primary Examiner—Jeffrey Asch[57] **CLAIM**

The ornamental design for a carrier handle, as shown and described.

DESCRIPTION

FIG. 1 is a perspective view of a carrier handle showing my new design;

FIG. 2 is a front elevation taken from the right of FIG. 1, and includes a hole in the front right flank;

FIG. 3 is a side elevation taken from the left of FIGS. 1, 2, 4 and 5, the right side elevation being identical;

FIG. 4 is a top plan view; and,

FIG. 5 is a rear elevation of FIG. 2, and is similar to FIG. 2, but does not have a hole in either flank.
